UNITED STATES PATENT OFFICE

ELMER T. GALLEY, OF PASADENA, CALIFORNIA

METAL WINDOW SCREEN

Application filed September 1, 1927. Serial No. 216,814.

An object of this invention is to provide an all-metallic window screen which will snugly fit the window frame and exclude at its points of union with the frame, weather, and having a minimum of projection from the face 5 of the window frame.

Another object is to provide a rigid all-metallic rectangular frame having at its inner margin a continuous channel into which the 10 edges of a section of wire cloth may be turned and held therein by a sectionally yielding fillet.

Another object is the saving of time in the placement of a section of wire screen in a 15 frame.

A feature of this invention is a cloth securing means which consists of an open-ended trough which receives the bent end of the wire cloth and a sectionally yielding retaining 20 strip which is forced into the trough over the turned end of the cloth.

An advantage arising out of the invention is the holding of a section of wire cloth uniformly at its edge in contra-distinction to the 25 securing of the cloth at intervals as is common.

Another advantage is that the wire cloth may be readily removed and a new cloth substituted therefor, without injury or distortion 30 of the frame.

Other objects, advantages and features of invention may appear from the accompanying drawings, the subjoined detailed description and the appended claims.

The accompanying drawings illustrate the invention.

Figure 1 is an inside elevation showing a fragment of a window frame and a screen constructed in accordance with my invention.

Fig. 2 is a fragmental sectional view on an enlarged scale on line x^2 , Fig. 1.

Fig. 3 is a transverse sectional elevation on line x^3 , Fig. 1 showing fragments of the upper and lower parts of the frame and fragments of the window screen showing the means for securing the screen frame in the window frame.

Fig. 4 shows a corner fragment of the screen frame taken from the inside of the window.

Fig. 5 is a view similar to Fig. 4 showing an exterior face.

Fig. 6 is an edge view of a screen frame suspension device.

Fig. 7 is an outside face view of the suspension device.

1 is a window screen constructed in accordance with this invention and is shown suspended from supports 2 secured to a window frame 3 embedded in a wall 4 a fragment of 55 which is shown. 5 indicates the stiles of the screen frame which are joined by rails 6, said stiles and rails having mitered ends 7 so that a neat joint can be effected. A gusset plate 8 so designed as to conform with the sectional configurations of the stiles and rails to cover each corner of the frame and is spot welded in place.

The screen frame has a flange 9 that overlaps the exterior of window frame 3 and 70 a rabbet 10 bent substantially at right angles thereto so that the rabbet 10 projects within the window frame and provides an additional seal between the screen and window frames.

The inner edge of each of the stiles and rails of the screen frame is reversely bent as at 11 so that the sides 12 and 13 are substantially parallel to provide a continuous groove 14 around the inner portion of screen frame.

A fillet 15 preferably made of wood, although wire or metal strips of requisite lengths, or metal bands of suitable proportions would be satisfactory for the purpose, is used to bind and lock bent-over portions of the wire cloth 16 in the groove 14. The fillet 15 has parallel sides 17 and 18 to conform with the sides 12 and 13 of the bent portion 11 so that as the fillet 15 is driven into the groove 14 it will press the wire cloth 16 against the side 13 of the portion 11 and simultaneously as the fillet is being driven home in the groove 14 it will drag the cloth 16 with it thus providing a means to draw the cloth taut. The outer edge of the fillet 15 has an arcuate surface 19 that adds to the symmetry of the finished screen, making it more pleasing to the eye.

The supports 2 are adapted to be secured

to the window frame 3 by means of screws 20 inserted in perforations 20' and each of said supports has flanges 21 projecting upwardly and outwardly from the shank of the support 2 so that the member 21 fits flush with the outer edge of the window frame. An arcuate tongue 22 integral with the member 21 is adapted to extend through a slot 23 in the overlapping flange portion 9 of the upper rail 6 and gusset plate 8 and said arcuate portion 22 provides a rest upon which the screen frame 1 is suspended. A hook 24 secured to the lower rail 6 is adapted to engage an eye 25 secured to the window sill 26, for the purpose of holding the screen snugly against the frame in closed position.

By reason of the continuous groove 14 and the fillets there is economy in wire cloth and economy in time in its securing to the frame. The wire cloth economy is due to the requirement of only a slight inturned margin of the cloth to "finish" over the exposed face of the trough. And the time economy is due to only a requirement of "turning" the edges of the cloth to direct them into the trough and the driving of a fillet into the trough along with the turned edge. And the window screen space economy is due to the fact that all members and parts are held within certain parallel lines, namely the outer flange of the frame and the inner edge of the rabbet and the inner bent-over portion of the groove as previously set forth, an advantage of which is that the whole of the window sill is unoccupied and that there are no parts projecting outwardly from the window frame.

I claim:

1. A metal window screen frame member comprising in its section a relatively flat flange for overlapping the face of a window frame; a relatively angular rabbet for engagement along the jamb of the window frame and at its margin opposite said flange a reversely bent channel.

2. A metal window screen frame member comprising in its section a substantially flat flange, a rabbet extended inwardly from said flange; a margin forming a channel having substantially parallel sides.

3. In combination with the mitered end of a stile and of a rail, each including in their sections a flange for overlying the face of a window frame; a rabbet for extension along the jamb of the window frame and a reversely bent margin forming a channel; of a corner plate covering the mitered ends of said frame members and sectionally shaped to conform therewith.

4. In combination with the mitered end of a stile and of a rail, each including in their sections a flange for overlying the face of a window frame; a rabbet for extension along the jamb of the window frame and a reversely bent margin forming a channel; of a corner

plate covering the mitered ends of said frame members and sectionally shaped to conform therewith; said corner plate being spot welded to the mitered ends of the frame members.

5. In a window screen frame comprising stiles and rails and constructed with a flange along the outer edge of said stiles and rails and with a rabbet at substantially right angles to said flange; bent-over portions along the inner edge of said stiles and rails to form a groove; said flange lying in approximately the same plane as the outer edge of the bent-over portion of the groove, and the inner edge of said rabbet and inner edge of the bent-over portion of the groove lying in substantially the same plane to effect a symmetry of proportions and economy of window screen space.

6. In a window screen frame support; a shank, a flange at right angles to said shank, a second flange bent upwardly and at right angles to said first flange and an arcuate tongue projecting outwardly and upwardly from said second flange; said shank and said first flange being perforated to receive securing means.

7. In a window screen frame support; a shank, a flange at right angles to said shank, said flange being sheer on one side of said shank and oppositely projecting from the other side of said shank, a second flange, said second flange being at right angles to said first flange and extending upwardly therefrom and an arcuate tongue projecting upwardly and outwardly from said second flange and means to secure said support to a window frame.

8. A metal window frame element, a section of which comprises a vertical flange for engagement over the face of a window frame; a substantially horizontal rabbet formed as an integral continuation of said flange for engagement along the jamb of a window frame; an element forming a continuation of the rabbet and bent to stand substantially in the plane of the flange, and a trough having sides which parallel said last mentioned element and having its end next the rabbet open to receive a sheet of wire cloth.

In testimony whereof, I have hereunto set my hand at Los Angeles, California, this 26th day of August, 1927.

ELMER T. GALLEY.
